(57) **CLAIM**

The ornamental design for a beverage dispenser with sight glass, as shown and described.

DESCRIPTION

FIG. 1 is a top, front, and right-side perspective view of a beverage dispenser with sight glass showing our new design; FIG. 2 is a front elevation view thereof; FIG. 3 is a rear elevation view thereof; FIG. 4 is a right-side elevation view thereof; FIG. 5 is a left-side elevation view thereof; FIG. 6 is a top view thereof; and, FIG. 7 is a bottom view thereof.

The broken lines in the drawings, namely the bottle handle, lid, tap handle, dimples, and bottom details, depict portions of the beverage dispenser with sight glass that form no part of the claimed design.
